(57) **CLAIM**

The ornamental design for a fidget toy as shown and described.

DESCRIPTION

FIG. 1 is a front, top perspective view of the fidget toy, showing my new design;

FIG. 2 is a rear, bottom perspective view thereof;

FIG. 3 is a front view thereof;

FIG. 4 is a rear view thereof;

FIG. 5 is a right side elevation view thereof;

FIG. 6 is a left side elevation view thereof;

FIG. 7 is a top view thereof;

FIG. 8 is a bottom view thereof; and,

FIG. 9 is front, top perspective view thereof, in an alternate configuration.

The broken lines in the drawings depict portions of the fidget toy and form no part of the claimed design.

1 Claim, 9 Drawing Sheets
